UNITED STATES PATENT OFFICE

JOHN E. OSTLINE, OF LIVERPOOL, ENGLAND, ASSIGNOR, BY MESNE ASSIGNMENTS, TO
AUTOMATIC ELECTRIC INC., OF CHICAGO, ILLINOIS, A CORPORATION OF DELAWARE

TELEPHONE SYSTEM

Application filed November 1, 1924, Serial No. 747,373, and in Great Britain November 14, 1923.

The present invention concerns improvements in or relating to automatic or semi-automatic telephone systems and more particularly those systems in which call indicator working is employed, although a number of 5 features of the invention are not limited to these conditions and may be applied in other circumstances than those immediately concerned with call indicator operation.

One of the features of the invention is a 10 special type of impulse repeater which is adapted to repeat the initial series of impulses received by it in one direction only and to repeat subsequent series of impulses in another direction only. This feature is of 15 particular value in connection with call indicator operation, in which it is often desirable that the necessary storage devices should be located at an automatic exchange and should be arranged to be common to as large 20 a group of junction lines as possible and not individual to a particular junction line or to a group of junction lines leading to a particular exchange. Under these circumstances it becomes necessary that the register devices 25 shall be taken into use prior to the transmission of the digit or digits serving for the selection of the particular exchange to which the call has to be routed and it is clearly unnecessary to store this digit or digits on the 30 register devices. Hence the necessity arises for the one or more series of impulses which determine the desired exchange to be repeated to a switch or switches in the speaking route in order to effect the exchange selection 35 and for subsequent series of impulses to be then repeated to the registering devices. An incidental advantage of this arrangement is that it permits ample hunting time for the 40 switch associated with the repeater serving to select an idle set of registering devices, since this time comprises the duration of a complete train of impulses and the pause at either end thereof.

When a repeater is employed such as that 45 described it will be apparent that the registering devices and the apparatus which may be associated therewith for sending out impulses over a trunk line in accordance with 50 the setting of the registering devices will be

used in common for trunk lines to various exchanges, which will be in general, of different lengths. Under these circumstances it becomes advantageous to provide compensating arrangements associated with the impulse 55 sender for varying the resistance in the impulse transmitting circuit in accordance with the characteristics of the inter-exchange trunk line over which the impulses are to be sent. This modification of the resistance can conveniently be effected by devices similar 60 to those used for registering the digits of the required number and adapted to be operated by a digit not forming part of the number to be transmitted over the trunk line.

Another feature of the invention concerns 65 an improved type of register set which consists of a single step-by-step switch adapted to respond successively to each of the digits to be recorded and after each response to transfer the digit recorded to one of a number 70 of groups of storage relays. This switch can conveniently be a 25-point rotary line switch of known type, arranged to have two normal positions and to move always in the same direction, and each group of storage relays may 75 comprise four relays which are energized in various combinations to make the necessary record.

According to a further feature of the invention a particular arrangement is provided 80 in connection with an impulse sender for sending in this case code impulses whereby the speed of the impulse generation may be accurately determined, and what is of more importance, as a result of the inevitable wear 85 of the contacts the speed will tend to decrease rather than to increase. Under these circumstances, adjustment may originally be made for the impulse generation to take place at a speed as high as is consistent with the reliable operation of the devices responsive thereto; there is then no danger of unreliable 90 operation of these devices in course of time, since the speed will tend to decrease rather than to increase. According to this arrangement the rate of generation of impulses is determined by a slow acting relay in conjunction with the controlling magnet of a step-by-step switch, the slow acting relay being 95 100

adapted to control the operating circuit of said magnet and to be short circuited until said magnet is fully energized. For instance, the relay may be normally short circuited by 5 an interrupter contact on the said magnet, the magnet in turn being energized over a back contact of the relay. A further advantageous arrangement contemplated according to the invention is to have a micrometer adjustment for this back contact so that 10 the speed of impulses generated may be accurately determined.

Still another feature relates to a special load distributing arrangement whereby calls 15 are distributed to each operator in turn irrespective of the number she has already awaiting attention. This sequence of operations is only disturbed if the number of calls awaiting attention at any particular position 20 reaches a predetermined number or if the cords at that position are in use or if the operator has left the position.

A further feature relates to an arrangement whereby calls requiring special service 25 not ordinarily provided by the regular call indicator operator can be routed to a special service operator by the momentary depression of a single special service key.

Yet another feature of the invention is concerned with an arrangement which comes into use momentarily when the transmission of 30 the required number over the trunk line has been completed to test whether the calling subscriber is still on the line. In case he is 35 not, the connection is then released and the number transmitted is not displayed to the manual operator.

These and other features not specifically mentioned at this point will be better understood 40 from the description of a preferred embodiment of the invention which will now be given with reference to the accompanying drawings, though it will be understood that this is by way of example only and that various modifications in the circuit details might 45 be made by those skilled in the art without exceeding the scope of the invention.

Figure 1 of the drawings shows a special 50 repeater at the tandem exchange, a coder selecting switch, a selector which responds to the final exchange selecting digit, and a secondary line switch at the incoming end 55 of the trunk line. This figure also shows a coder, that is to say a device for registering the digits dialled together with a code sending switch for transferring these digits to the distant call indicator position in a particular code.

Figure 2 shows a trunk relay group and a 60 special service trunk finder, and also the necessary switches for determining the sequence in which calls shall be dealt with by 65 the de-coder and a special switch for dis-

tributing the load equally among the various operators.

Figure 3 shows the call indicator lamps and the de-coder, the function of the latter being to respond to the code impulses sent 70 over the trunk line and to control the lighting of the appropriate call indicator lamps so as to display the number to the operator.

Figure 4 shows a cord circuit and the rotary line switch associated therewith together with the meters, supervisory apparatus and operator's equipment, and also a special service trunk finder and a special service trunk.

Figure 5 is a diagrammatic representation 80 of the general lay-out of the system from which main principles underlying it may be gathered, while Figure 6 is a table showing the code into which the various numerical digits are converted for sending over the 85 trunk line.

A description will first be given of the general lay-out shewn in Fig. 5 where it will be assumed that a connection is to be extended from the calling subscriber A to the called subscriber A'. When the calling party A removes his receiver, his individual line switch C will operate to select an idle trunk relay group TR with which is then associated an idle register selector B. Upon receipt of 90 the first digit this will be operated for instance to the eighth level and will then operate to select an idle director such as DI. The first selector E also responds to the first series of impulses and then operates to select a selector such as E'. The director DI will then register the remainder of the digits and send out suitable trains of impulses which will in general be different from those sent by 95 the calling subscriber.

The first of these trains will operate a selector such as the selector E', the wipers of which will be raised for instance to the eighth level and will then automatically be rotated in search of a free trunk to a repeater such as 100 R. The repeater R is of special type so arranged that the first series of impulses received by it are repeated to a succeeding selector such as D, while subsequent series of 105 impulses are repeated over the coder selector CS to a coder which comprises all the apparatus enclosed in the dotted rectangle. Accordingly when the next digit is sent, the selector D will be operated, for instance, to the sixth level and will then select an idle trunk line to the secondary line switch SL at the 110 required manual exchange.

During the transmission of this digit the 115 coder selector CS will have selected an idle coder and subsequent digits transmitted will be directed to the digit recording switch DRS and will thereupon operate in turn the compensating relay CR and the relays in the storage groups SG¹, SG², SG³ and SG⁴. The 120 125 130

purpose of the compensating relays CR is to adjust the resistance of the trunk line to standard value as will be more fully understood from the detailed description which follows. As soon as all the digits have been sent, the secondary line switch SL is set in operation to select an idle trunk relay set D' from among those rendered accessible by the load distributing switch LDS operating in conjunction with the position load distributing relay set LR. At the same time an idle marker S' allotted by the marker distributor S² is taken into use and this in conjunction with the set-up control switch S³ in due course effects the connection of the trunk relay group D' to the de-coder D²; this will occur when the de-coder has dealt with calls which have come in prior to the one under consideration. When the trunk relay group D¹ is connected with the de-coder D², the sending switch S in the coder is started up to send in code over the trunk line the digits stored on the storage relay groups SG¹, SG², SG³ and SG⁴. When this process is completed the coder is released and reverts to common use and the number transmitted over the trunk line in code having been de-coded at the de-coder is displayed by means of the storage relay groups D³ on the lamps L at the operator's position.

The operator then inserts the plug attached to a cord in the most convenient position into the jack of the wanted subscriber, whereupon the trunk finder TF will be started up to find the trunk relay set which has been used. When this is found, the called subscriber will be rung and when he answers conversation may proceed in the usual manner. The de-coder is released as soon as the operator inserts the plug and the set-up control switch S³ is then moved on into association with the next marker which has a call waiting to be dealt with. Upon the termination of the conversation the operator will be notified in the usual manner and will withdraw the plug, whereupon all the operated apparatus will be released.

In case the operator sees from the number which has been dialled that some special service is required which in the ordinary way it would not be her business to give, she will press the special service key at her position, whereupon instead of the trunk finder TF being started up, the special service position trunk finder STF is operated to find the particular trunk relay set in the manner previously described. When it has been found the special service trunk finder SST is started up to select a trunk leading to a jack such as SS at a special service operator's position over which the call may be dealt with by the special operator. The regular operator need only press the special service key momentarily and the de-coder is then released and the

subsequent connections are made entirely automatically.

The operation of the system having been described in general terms, a detailed description will now be given with reference to the circuit diagrams Figures 1, 2, 3 and 4 which should be placed together with the corresponding lines in alignment. Portions of the circuits are very similar to those disclosed in copending application No. 27,819 of 1923, but there are important differences as will be pointed out.

It will be assumed that the repeater in Fig. 1 is taken into use from the bank of an incoming selector such as E'. As soon as the selector switches through, the following circuit is completed: battery, upper winding of relay 4, normally closed springs controlled by armature 45, upper trunk conductor 1, impulsive loop at the director, lower trunk conductor 2, normally closed springs controlled by armature 46, lower winding of relay 4 to earth. Relay 4 upon operating, at its armature 5 completes a circuit for release relay 7 and at its armature 6 prepares the impulsive circuit. Relay 7 operates when its circuit is completed, at armature 9 connects earth to release trunk conductor 3, at armature 10 completes a circuit for the right hand winding of the shunt field relay 15, at armature 54 prepares a circuit for the series relay 11 and at armature 8 completes a circuit for relay 31 which extends as follows: battery, upper winding of relay 31, back contact and armature 18, front contact and armature 8, armature 9 and its front contact, earth. Relay 31 thereupon operates and at armature 32 connects earth to the release trunk conductor 49, though this operation is without effect at the moment. A circuit is also completed by relay 7 for starting up the coder selector switch as follows: battery, winding of line relay 33, back contact and armature 40, normally closed springs controlled by armature 23, back contact and armature 18, front contact and armature 8, armature 9 and its front contact, earth. By operating its armatures 34 and 35, relay 33 starts the coder selector hunting for an idle coder in known manner.

In response to the transmission of the next digit, a corresponding number of interruptions will be produced in the circuit of line relay 4 and it will de-energize accordingly. As soon as relay 4 first pulled up, a circuit was completed over the trunk conductor 48 which circuit extends as follows: from battery by way of resistance 75, back contact and armature 28, front contact and armature 6, armature 30 and its back contact, back contact and armature 24 to conductor 48, and through the lower winding of the line relay (not shown) of the selector D to ground. Consequently each time relay 4 deenergizes, this bridge is opened at armature 6 and the succeeding se-

lector D, indicated by the dotted rectangle, is operated accordingly. Upon the first deenergization of relay 4, a circuit is completed over armatures 10 and 13 for series relay 11 which energizes and being slow to release, remains energized throughout the series of impulses. Relay 11 upon operating, at its armature 12 opens another point in the connection between release trunk conductor 3 and release trunk conductor 49 and at its armature 13 completes a circuit for the lower winding of relay 25. This relay is of the two-step type and in response to current flowing through its lower winding operates its lightly adjusted armature 27 whereupon earth is connected to both ends of its upper winding.

When the first series of impulses ceases, the selector D will hunt in known manner to find an idle trunk line to the required manual exchange, and having found one, will switch through. After having switched through, the selector D is held up by earth on release trunk conductor 49 by way of armature 32. The conductors 47 and 48 are now extended to the conductors 200 and 201 leading to the position selector having wipers 230, 210 and 231. The position selector is not operated at this time, however, notwithstanding the battery connection thru resistance 75 to conductor 48, as conductor 47 over which the line relay 206 must be operated is free from operating potential at this time.

On the termination of the series of impulses and after a sufficient time has lapsed to permit the selector D to complete the above mentioned trunk hunting operation and switch through, relay 11 deenergizes and earth is then removed from the middle point of the winding of relay 25 which accordingly operates fully, and at its armature 26 opens a point in its original energizing circuit, at armatures 28 and 30 opens the bridge across conductors 47 and 48 and at armature 29 and the front contact of armature 30 prepares a new impulsive circuit so that succeeding trains of impulses are sent to the coder, while at the front contact of armature 28 a circuit is prepared for relay 20.

In the meantime, the coder selector will have been hunting to find an idle coder, and when test wiper 53 engages a contact which is not earthed, switching relay 38 is not longer short circuited and energizes in series with rotary magnet 36 which is however not now operated. Thereupon wipers 50 and 51 are connected through to the outgoing trunk conductors at armatures 39 and 43, at armature 40 relay 33 is disconnected and at the front contact of this armature and the front contact of armature 41 earth from armature 9 is connected to the test wiper 53, while at the front contact of armature 42 the impulsive circuit is prepared.

Upon the transmission of the next digit, 65 the following circuit is completed on each

deenergization of relay 4: battery, winding of magnet 80 of the digit recording switch, winding of series relay 65, back contact and armature 74, lead 62, wiper 52, front contact and armature 42, front contact and armature 30, armature 6 and its back contact, armature 29 and its front contact, armature 10 and its front contact to earth. The digit recording switch is thus advanced by the operation of its driving magnet a number of steps corresponding to the value of the digit dialled. Relay 65 is energized in series with the magnet and at its armature 65 completes a circuit for relay 67. This relay thereupon at its armature 68 prepares a circuit for operating the storage relays and at armature 69 prepares a circuit for the relay 98.

At this point it may be desirable to explain the purpose and operation of relays 92 and 93. It will be clear from what has already been said that access may be had from the repeater in Fig. 1 to any one of a number of exchanges as determined by the setting of the selector D. Furthermore the length of the trunk lines leading to the different exchanges may vary considerably and as the coder at the distant exchange contains relays which are marginally operated by currents over the trunk line, it will be apparent that some difficulty or at least inconvenience may be caused by the fact that these relays in the various decoders at the same exchange in order to operate reliably will have to be differently adjusted so as to respond correctly to codes transmitted from a number of other exchanges. In order to overcome this difficulty and to permit a standard adjustment of the relays in question, the compensating relays 92 and 93 have been introduced at the de-coder. The operation of these relays is controlled by sending an extra digit immediately preceding those which are to operate the storage relays in the coder and are subsequently to be displayed at the call indicator position. This is particularly easy to achieve if, as in the arrangement now being described, the digits dialled by a subscriber are received by a register translator or director from which impulses are sent out which will in general be different from those received by the director. The sending of an extra train of impulses in this case can be effected by making an additional cross connection to the impulse sender. The digit for effecting the compensation will preferably be either 1, 2, 3 or 4 and in response thereto either one or both or neither of the relays 92 and 93 will be operated. The contacts 94 and 96 controlled by them are arranged to short circuit the resistances 104 and 105 respectively, which are connected in the circuit over which the code impulses are sent.

Let it be assumed in the present instance, 130 that the digit sent for compensating pur-

poses is 3 and that the wanted subscriber's number subsequently recorded in the coder is 4567. In response to the compensating digit 3 therefore the wipers 82, 83, 84 and 85 of the digit recording switch will be moved three steps, so that the wiper 82 comes into engagement with contact 106, while wiper 84 comes into engagement with contact 107. At the end of the series of impulses, relay 65 deenergizes and a circuit is then momentarily completed from earth, armature 66 and its back contact, armature 68 and its front contact, wiper 82, contact 106, lead 89, armature 99 and its back contact, winding of relay 93 to battery, and parallel thereto over wiper 83, contact 107, lead 90, armature 100 and its back contact, winding of relay 92 to battery. Relays 92 and 93 upon operating, at armatures 95 and 97 lock themselves up to the holding earth in the repeater by way of armature 73 and its back contact, and lead 63, and at armatures 94 and 96 remove the shunts around resistances 104 and 105, respectively, so that both these resistances are included in the code sending circuit over the trunk conductors: this case will clearly correspond to a short trunk line to a nearby exchange. A circuit is also completed on the deenergization of relay 65 from earth at armature 66, armature 69 and its front contact, armature 103 and its back contact, upper winding of relay 98 to battery. Relay 98 is also of the two-step type similar to relay 25 and thereupon operates its light contact 102. Upon the deenergization of relay 67, earth is removed from the middle point of the winding of relay 98 and it then operates fully; at its armature 103 transfers its original energizing circuit to relay 108 and at armatures 99, 100 and 101 connects the leads from the various bank contacts of the digit recording switch through to the relays of the first storage group. When armature 69 engages with its back contact a circuit is completed over the multiplied contacts in the bank of wiper 85 and said wiper and interrupter contact 81 for automatically restoring the digit recording switch to normal. This switch will from the nature of things never have to take more than 10 steps to respond to a particular digit and as it is convenient to use for this purpose an ordinary rotary line switch moving always in the same direction, which switch has 25 contacts, it will probably be desirable to multiply the contacts of the bank together in two halves so that the switch will have two normal positions. In this case therefore the switch will come to rest with wiper 85 resting on the dead contact 86.

The digit 4 will now be sent out from the director, in accordance with which the wipers of the digit recording switch will be advanced four steps. When relay 65 deenergizes, a circuit will be completed from earth,

armature 66 and its back contact, armature 68 and its front contact, wiper 82, contact 109, lead 88, armature 101 and its front contact, armature 110 and its back contact for relay 111. Relay 111 at armature 112 completes a locking circuit for itself to the earth on the repeater and at armature 113 prepares a circuit for sending the appropriate code impulses. Wipers 83 and 84 both come to rest on dead contacts in this case so that no other relays in the first storage group are operated. Relay 108 is partially energized when earth is connected to the middle point of its winding over armatures 69, 103 and 115 and thereupon operates its light contact 114. When earth is removed on the deenergization of relay 67 relay 108 pulls up fully and at armature 115 transfers the connection over lead 116 to relay 117, and at armatures 118, 119, 110 and 120 transfers the connections of leads 88, 89, 90 and 91 to the second storage relay group.

The next digit on the assumption made above is 5; consequently upon the receipt of this digit the wipers 82, 83, 84 and 85 are stepped around into their fifth position. When relay 65 releases, a circuit is completed over wiper 84 for relay 121 which operates to prepare the code sending circuit at armature 122 and at armature 123 locks itself up. Relay 117 is similar to relays 108 and 98 and is partially energized when relay 65 releases and is fully energized when relay 67 releases and thereby transfers the operating circuits to the third storage group.

When the next digit 6 is sent, the digit recording switch takes six steps, whereupon on the deenergization of relay 65 circuits are completed over wipers 82 and 84 for relays 125 and 126 which lock up and prepare code sending circuits in the manner previously described. Relay 124 is operated fully when armature 69 leaves its front contact and transfers the operating leads to the fourth storage group and the connection over lead 116 to relay 127.

The transmission of the last digit 7 results in the operation of relays 128 and 129 which lock up and prepare code sending circuits in the same manner as the other storage relays. Relay 127 operates its light contact 130 when earth is first connected to the middle point of its winding over lead 116 and when this earth is removed operates fully. At armatures 131, 132, 133 and 134 the circuits for the fourth set of storage relays are opened so as to prevent any accidental further operation, at armature 135 relay 127 opens its own initial energizing circuit, at armature 136 it opens the initial energizing circuit of relay 75, at armature 137 prepares a holding earth connection to lead 63 and at armature 138 prepares a circuit over lead 139 for starting the sending of code impulses. Relay 75

was energized over armature 136 and its back contact at the same time as relay 127 was partially energized and at armature 78 opened the code impulse starting circuit, and 5 at armature 76 removed earth from armature 137. Relay 75 also by operating its armatures 77 and 79 connected itself over its upper winding in a locking circuit which extends as follows: battery, winding of line relay 10 206, of the incoming secondary line switch, back contact and armature 203, upper trunk conductor 200, through the selector D, conductor 47, armature 21 and its back contact, armature 39 and its front contact, wiper 50, 15 lead 60, armature 79 and its front contact, upper winding of relay 75, front contact and armature 66, lead 61, wiper 51, front contact and armature 43, back contact and armature 24, conductor 48, through the selector D, conductor 201, armature 204 and its back contact, earth.

Relay 206 is energized in this circuit and by operating its armatures 207 and 208 starts the incoming rotary line switch hunting for 25 a free trunk over which the connection may be completed. This hunting operation takes place in known manner and as soon as an idle trunk is found, relay 202 being no longer short circuited, energizes in series with magnet 209 and at its armatures 203 and 204 disconnects relay 206 and connects the trunk leads through, while at armature 205 it completes a locking circuit for itself. Relay 75 is not deenergized by the momentary opening 30 of its circuit consequent on the operation of its armatures 203 and 204, and when this has taken place, the circuit for maintaining it energized extends as follows: from battery, upper winding of relay 212, back contact and armature 225, back contact and armature 224, 35 back contact and armature 223, the trunk conductor 220, wiper 230, front contact and armature 203, conductor 200, thence over the previously traced circuit to conductor 201, armature 204 and its front contact, wiper 231, 40 conductor 221, armature 226 and its back contact, armature 227 and its back contact, armature 228 and its back contact, armature 229 and its back contact, earth.

50 Before proceeding further with the description of the actual operation of setting up a call, it will be desirable to explain the circumstances under which a trunk such as that shown in Figure 2 is rendered accessible to an incoming secondary line switch. In order 55 to ensure that calls shall be distributed equally among the operators so that no one operator receives more or less than her fair share, a set of position load distributing relays is provided for each position and these operate in conjunction with a load distributing switch which is common to a group of positions. The effect of these arrangements is that for each call that comes in a definite operator's 60 position is preselected so that the calls are

distributed to each operator in turn until they have each received one, the subsequent distribution being continued in the same manner irrespective of whether the first call has been dealt with or not. Arrangements are 70 also provided to prevent more than a certain number, in this case five, calls accumulating at any operator's position and should this condition of affairs arise, an alarm is given to a supervisor to indicate that the position is 75 overloaded. A position is also rendered inaccessible if the operator leaves it or if all her cords are in use as will be more fully explained hereafter.

Suppose in the present instance that the 80 position at which the trunk shown is located has two calls awaiting attention and that the wipers 242 and 243 of the load distributing switch have just arrived again on the contacts 244 and 245 associated with this 85 position. In these circumstances relay 234 will be energized in the following circuit: earth, armature 241 and its back contact, wiper 242, contact 243, winding of relay 234 to battery. The operation of relay 234 which 90 then takes place closes contact 237 whereby a locking circuit is prepared for relay 233 and contact 238 whereby an energizing circuit is prepared for relay 233 and earth is removed from the position busy common lead 232 so as 95 to render the idle trunks in this position selectable. When the switching relay 202 of the incoming rotary line switch switches through a circuit is momentarily completed as follows: earth, front contact and armature 100 207, front contact and armature 205, wiper 210, release trunk conductor 222, normally closed springs controlled by armature 218, common lead 232, armature 235 and its front contact, winding of relay 233 to battery. Relay 233 accordingly operates, at armature 105 235 completes the previously prepared locking circuit for itself and at armature 236 completes a circuit extending from earth, front contact and armature 235, contact 245, wiper 243, relay 239 to battery. Relay 239 upon operating, at armature 241 opens the circuit of relay 234 and at the front contact of this armature completes a circuit for the driving magnet 240 so that the distributing 110 switch takes one step. Relays 233 and 234 are thus deenergized and earth is replaced on the common lead 232. It is then impossible for any further calls to come to the position in question until a call has been received 115 by each of the other positions unless they are inaccessible for any of the reasons mentioned above. In such a case, earth would be connected to the lead corresponding to lead 246 and relay 239 would be again energized 120 over the back contact of the armature corresponding to armature 236. The distributing switch therefore takes a further step and no 125 call is received at that particular position.

To return now to the consideration of the 130

operations taking place in the trunk relay set, relay 212 energizes in series with relay 75 when the line switch switches through. Thereupon at its armature 213 it completes a circuit for relay 217, at armature 214 prepares a locking circuit for itself, at armature 215 prepares a circuit for relay 247 and removes earth from contact 302 in the bank of wiper 300 and at armature 216 connects earth over the common lead 316 to the wiper 317 of the marker distributor.

It should be explained that in order to ensure that calls arriving at a position are dealt with in the proper order, a number of markers are provided, in the case considered five, this representing the maximum number of uncompleted calls that it is desirable should exist simultaneously at any one position. These markers have two banks which are connected to the various trunk relay sets in the position. The order in which the markers are taken into use is controlled by a marker distributor, of which only one is provided per position and it is further necessary to have a set up control switch, the function of which is to connect up the de-coder in turn to various trunks which have been taken into use so that the number may be sent in the special code from the recording devices at the tandem exchange, so as to operate the proper lamp and indicate to the operator the wanted number. The necessity for the set up control switch as well as the marker distributor is on account of the difference in the rate at which calls arrive at the position and the rate at which the operator deals with them. Thus if four calls come to a position almost simultaneously the marker distributor will operate to assign four markers in quick succession; the set-up control switch, however, will lag somewhat and will move on to permit the display of the fourth call after the other three have been displayed and dealt with.

Let it be assumed that when the call arrives the marker distributor is in the position shown, the marker shown is in any other position and the set up control switch wipers are resting on the contacts next before those with which they are shown in engagement. Accordingly when relay 212 operates a circuit will be completed as follows: earth, armature 252 and its back contact, front contact and armature 216, common lead 316, wiper 317 of the marker distributor, contact 318 associated with the marker shown on which it is resting, armature 311 and its back contact, winding of relay 312 to battery. Relay 312 is thereupon energized and by operating its armatures 313 and 314 starts the selected marker hunting for the contact 302 in the bank wiper 300, from which earth has been removed by the operation of armature 215. When this contact is found, relay 305 is no longer short circuited and energizes, thereby at contact 311 opening the circuit of relay 312 and at contact 310 completing a locking circuit for itself. Furthermore at armature 309 a circuit is completed for the driving magnet 324 of the marker distributor which thereupon operates so as to allot another marker and at armature 308 a circuit is completed for relay 327 in the set-up control switch. Relay 305 also at armature 306 removes one earth connection from lead 337 of the chain busying circuit and at the front contact of this armature lights the marker pilot lamp 469 at the operator's position so as to indicate which marker is in use, at the same time by operating relay 470 lighting lamp 472 to show that a call is awaiting attention. As a further result of the energization of relay 305, earth is removed from contact 326 in the bank of wiper 325 of the set-up control switch so as to render the trunk accessible and at the front contact of this armature an operating circuit through the set-up contact switch is prepared which will be more fully described subsequently. When armature 310 engages with its front contact, the following circuit is completed: earth, front contact and armature 313, front contact and armature 310, wiper 300, armature 302, armature 215 and its front contact, lower winding of relay 247 to battery. Relay 247 thereupon operates, at its armature 245 prepares a circuit for relay 259, at armature 249 prepares a locking circuit for relay 260, at armature 250 prepares a locking circuit for itself through its own upper winding, at armature 251 completes a locking circuit through its own lower winding which circuit also serves to maintain relay 305 energized, at armature 252 removes earth from the marker start common lead 316 and at armature 253 prepares a locking circuit for relay 254.

The operation of the set-up control switch must now be considered. As has been already mentioned, it is assumed that wiper 325 is standing on the contact immediately before contact 326 and that the de-coder is connected to the trunk corresponding to this contact. Under these circumstances, relay 327 will be energized by earth over the armature similar to 308 of the marker in use for the other connection and relay 330 will also be energized. This state of affairs will continue until the call has been completely decoded, whereupon in a circuit which will be traced subsequently, the earth connected to the contact upon which wiper 325 is standing is removed momentarily and is then replaced over the bank contact of the armature corresponding to 307 in the other marker. When this occurs, relay 230 deenergizes, but owing to the operation of armature 308, relay 327 will remain energized and a circuit will consequently be again completed over armatures 328 and 331 for relay 334. This relay, by operating its armatures 335 and 336, starts the set-up control

switch hunting. In the case under consideration it will only have to take one step and it will then encounter the contact 326 from which earth has been removed by the operation of armature 307. Relay 330 thereupon energizing, at armature 331 opens the circuit of relay 334 and at armature 332 completes the following circuit, earth, front contact and armature 335, front contact and armature 352, 5 front contact and armature 329, wiper 325, contact 326, armature 307 and its front contact, wiper 301, contact 303, winding of relay 254, armature 214 and its front contact, lower winding of relay 212 to battery. The 10 circuit thus completed serves to maintain the relay 212 energized when its upper winding is disconnected on the operation of relay 254. Relay 254 at its armatures 224 and 227 connects the trunk leads 220 and 221 through by 15 way of the leads 276 and 277 to the code receiving relays 501, 502 and 503, at armature 255 prepares a testing circuit for a purpose which will be explained subsequently, at armature 256 completes a locking circuit for 20 itself which also serves to maintain relay 330 energized after relay 334 releases, at armature 267 completes a circuit for relay 500 and at armature 258 prepares a circuit through the 25 lower winding of relay 260.

30 In consequence of the operation of relay 254 the feeding current is disconnected from the winding of relay 75 at the coder and in consequence thereof it deenergizes after a short interval. A circuit for starting the sending 35 of the code impulses is then completed as follows: earth, armature 76 and its back contact, armature 137 and its front contact, back contact and armature 73, armature 138 and its front contact, armature 78 and its back contact, lead 139, first contact in the bank of 40 wiper 142 and said wiper, lead 146, armature 71 and its back contact, lead 147, winding of magnet 143 to battery.

45 It will be as well to describe at this point the inter-operation of magnet 143, its interrupter contact 144 and the relay 70. Relay 70 is arranged to be normally short circuited by the interrupter contact 144 over leads 145 and 146 but when the contact 144 is opened on the 50 operation of the magnet it is enabled to energize and thus opens its own contact 71, whereby the circuit of the magnet 143 is opened and it releases. The contact 71 is provided with a micrometer adjustment, the operation of which serves to determine accurately the rate of generation of impulses. This 55 adjustment is normally set to effect the generation of impulses at a rate which is as high as possible consistent with the reliable operation of the devices controlled thereby and 60 in case any wear should occur, the effect will be to make the generation of impulses take place at a somewhat slower rather than a quicker rate; consequently there is no danger 65 of faulty operation due to impulses being sent

too quickly when any such wear has taken place after the lapse of time. If and when the reduction in speed becomes appreciable it is a comparatively simple matter to re-set the contact 71 of the relay 70 by means of the micrometer adjustment so that the impulses will again be generated at the maximum permissible rate.

70 Returning now to the operation in this particular case, the code sending switch thus 75 commences to rotate its wipers when the above circuit is completed. On the first step wiper 142 finds earth over its second contact, all the contacts in the bank of wiper 142 being multiply connected to earth with the exception of two, one corresponding to the normal position of the switch which is connected to lead 139 and the twenty third contact 148 which is connected to lead 149 and controls the release of the coder in a manner which 80 will be described fully hereafter. The effect of these multiplied contacts is that as soon as the switch is stepped off normal, it continues to step round under the joint control of interrupter contact 144 and the contact 71 85 of relay 70 until it again reaches normal position. Wipers 140 and 141 of the code sending switch are connected respectively to the lead 60 and 61 and thence over the trunk line 90 to the relays 501, 502 and 503 in the decoder. The banks of these wipers are so connected up 95 that for each digit which it is desired to send in code the switch takes four steps.

100 The impulses sent over the trunk line are of three kinds which may be termed positive, light negative and heavy negative, and of 105 the relays which respond to them, relay 501 is polarized in such a manner as to respond to what is termed a positive impulse, relay 503 is polarized in the opposite direction so as to 110 respond to a negative impulse while relay 502 is marginally adjusted and will only respond when a stronger current is sent over the line, this corresponding to what has been termed a heavy negative impulse since no heavy positive impulses are employed. It is also arranged for reasons which will appear subsequently that a negative impulse, either of the light or heavy variety is always sent out 115 on the second and fourth of the four steps of the sender switch, while a positive impulse may be transmitted only on the first and third steps. The combinations of these impulses 120 which are used to characterize the various digits are shown in the table in Fig. 6 which also indicates which relays (assumed numbered from right to left) of a storage group must be operated in order that these particular impulses shall be generated.

125 In the present case it will be remembered that the number received by the coder was 34567, of which the first digit 3 was only employed for determining which compensating resistance, if any, should be included in the circuit: consequently it is clearly unnecessary 130

and undesirable that this should be transmitted to the de-coder. The relays 92 and 93 therefore, operated by the compensating digit have no contacts having direct connection with the banks of wipers 140 and 141.

Since in accordance with the digit 4, only relay 111 of the first storage group is operated, when the code sending switch arrives at the position for sending the first impulse for the first digit, that is to say, after taking two steps from its normal position, no circuit will be completed; consequently no effect is produced at this time.

On the next step, however, an impulse is sent over the following circuit: battery, resistance 105, resistance 104, high resistance 151, back contact and armature 154, contact 150, wiper 140, lead 60, wiper 50, front contact and armature 39, back contact and armature 21, conductor 47, conductor 200, armature 203 and its front contact, wiper 230, conductor 220, armature 223 and its back contact, armature 224 and its front contact, lead 276, relay 501, relay 502, relay 503, lead 277, front contact and armature 227, back contact and armature 226, conductor 221, wiper 231, front contact and armature 204, lead 201, lead 49, armature 24 and its back contact, armature 42 and its front contact, wiper 51, lead 61, wiper 141, contact 153 to earth. Current in this direction constitutes what is understood as a negative impulse and as the high resistance 151 has been included in the circuit rather than the low resistance 152 it will be a light negative impulse and consequently only relay 503 will be operated. A circuit is therewith completed as follows: earth, armature 506 and its front contact, armature 505 and its front contact, armature 516 and its back contact, lower winding of relay 509 to battery. Relays 508 and 509 are each of the two-step type having a light contact which alone is operated when the relay is energized through one winding only: consequently armature 518 is now operated. On the termination of this impulse, when the code sending switch steps on to the next contact and relay 503 is deenergized, relay 509 pulls up completely, at armature 512 prepares a locking circuit for relay 508, at armatures 514 and 515 alters the connections to the first set-up relay group, and at armature 516 opens its own initial energizing circuit and prepares circuits for the lower windings of relays 508 and 517.

When the code sending switch advances to its next position, a circuit is completed in consequence of the operation of relay 111 as follows: battery, resistance 105, resistance 104, high resistance 151, front contact and armature 113, fourth contact in the bank of wiper 141 and said wiper, lead 61, wiper 51, front contact and armature 43, back contact and armature 24, conductor 48, conductor 201, armature 204 and its front contact, wiper

231, conductor 221, armature 226 and its back contact, armature 227 and its front contact, lead 277, relay 503, relay 502, relay 501, lead 276, front contact and armature 224, back contact and armature 223, conductor 220, wiper 230, front contact and armature 203, conductor 200, conductor 47, armature 21 and its back contact, armature 39 and its front contact, wiper 50, lead 60, wiper 140, fourth contact in its bank, earth. It will be noticed that the direction of current flow in this circuit is opposite to that in the circuit previously traced and that this current accordingly constitutes a positive impulse. The effect of this positive impulse is to operate only relay 501 which completes a circuit as follows: earth, armature 506 and its front contact, armature 507 and its front contact, armature 514 and its front contact, armature 523 and its back contact, relay 524 to battery. Relay 524 thereupon operates, at its armature 525 locks itself up by way of lead 526 to the earth on armature 506 and at its armature 527 prepares a circuit of the upper winding of relay 528.

The code sending switch will now take another step whereupon a light negative impulse will be transmitted over a circuit precisely similar to that previously traced for such an impulse; the effects at the de-coder are however slightly different in this case, owing to the operation of relay 509. As soon as relay 503 picks up, a circuit is completed for the lower winding of relays 508 and 517 which thereupon operate their light contacts 511 and 518, respectively, thereby short circuiting their upper windings. On the termination of the impulse when armature 505 leaves its front contact, both these relays energize fully over their two windings in series. Relay 508 at its armature 510 opens the locking circuit of relay 509, which thereupon deenergizes and at armature 512 opens the locking circuit of relay 508 so that both these relays are thus deenergized. Relay 517 operates its contacts 519, 520, 521, 522 and 523 whereupon its own energizing circuit is transferred to a similar relay of the set corresponding to the second digit and the operating circuits are transferred to the second set-up relay group. The set-up and storage relays corresponding to the second and third digits are not shown since they are similar in all respects to those for the first digit; their position is indicated by the dotted rectangles.

The next digit to be transmitted in code is 5 and reference to the table in Fig. 6 will show that this is done by sending a light negative impulse followed by a heavy negative impulse. The effect of the initial light negative impulse is similar to that described previously, namely, that relay 509 is energized and locked up but that none of the set-up relays is energized.

Upon the receipt of the following heavy negative impulse, relay 502 is operated as well as relay 503 whereby a circuit is completed over armature 504 and its front contact, armature 515 and its front contact, armature 521 and its front contact for the fourth relay in the second set-up group which thereupon locks up to lead 526 and prepares a circuit for the corresponding relay in the storage group. This impulse also has the effect of energizing relay 508 and the change-over relay corresponding to 517 after which both relays 508 and 509 deenergize, and the circuit is left in readiness for the receipt of the next digit.

The digit 6 now to be transmitted involves the sending of a positive impulse in the first position of the code sending switch for this digit, that is to say, with the wipers resting on the eleventh contacts. A circuit substantially identical with that over which this impulse is sent has been traced in connection with the sending of the digit 4 and it need not be repeated. The effect of the de-coder is to energize the first relay in the third set-up group which thereupon locks up and prepares the circuit for the corresponding storage relay as before. The light negative impulse which is then sent merely serves to operate the relay 509. In the next position of the sending switch no impulse is sent at all and in the following position a heavy negative impulse which as previously described operates the fourth relay of the set-up group and restores relays 508 and 509 to normal.

The final digit 7 is sent by means of two negative impulses, the first of which effects the operation of the second relay 530 in the fourth set-up group. This relay locks itself up at its upper armature and at its lower armature prepares a circuit for its corresponding storage relay. Relay 509 is also energized and locked up by this impulse in well known manner. The succeeding heavy negative impulse effects the completion of a circuit for the fourth set-up relay 533 which operates in a similar manner to the others. Relays 508 and 509 restore to normal in the usual manner and upon the termination of the impulse relay 531 is energized. This operates armatures 529, 532, 534 and 535 whereby the fourth digit relay set is disconnected so as to prevent any subsequent accidental operation; at armature 536 opens the circuit of relay 542 which has previously been energized though in this case without useful function, at armature 537 prepares a circuit for energizing the storage relays and at armature 538 prepares a circuit for relay 543.

For the sake of convenience of description it will be assumed that when the decoder is taken into use for the call under consideration the operator has already dealt with the previous call and consequently there is no number displayed on the call indicator lamps.

This assumption is not altogether consistent with the previous assumption employed for explaining the operation of the set-up control switch but this is immaterial as regards the proper working of the apparatus and simplifies the description of the subsequent operations. With this assumption therefore, a short while after the energization of relay 531, after relay 542 has deenergized owing to its circuit being opened at armature 536, the following circuit is completed: earth, armature 544 and its back contact, armature 547 and its back contact, armature 537 and its front contact, armature 549 and its back contact, lead 552 to battery through the upper windings of the storage relays whose circuits have been previously prepared by the operation of their corresponding set-up relays. The storage relays thereupon operate and lock up to lead 553 to which earth is connected over armature 506 and its front contact, normally closed springs controlled by armature 546 and armature 548 and its back contact.

The earth connection to lead 552 also extends over armature 258 and its front contact through the lower winding of relay 260 to battery so that this relay is operated. At armature 261 it closes another point in the circuit of relay 259, at armature 263 prepares a circuit for relay 266, at armature 264 removes earth from test contacts 273 and 274, at armature 265 opens the locking circuits of relays 212 and 251 and at armature 229 removes earth from the lower trunk conductor and substitutes battery for a purpose which will be described subsequently. Relay 260 also at its armature 262 completes the following locking circuit for itself; earth, back contact and armature 268, upper winding of relay 260, front contact and armature 262, back contact and armature 270, front contact and armature 249, lead 272, lower winding of relay 539 to battery. Upon the release of relays 212 and 254, the trunk relay set is disconnected from the common leads to the de-coder, and earth is removed from the contacts engaged by wiper 300 of the marker and wiper 325 of the set-up control switch. In consequence, relay 305 is deenergized and the marker is rendered available for use in setting up another connection and the set-up control switch steps on as previously explained and controls the association of the de-coder with another trunk relay group.

Relay 539 operates when its circuit is completed, at armature 545 completes a circuit for relay 540, at the same time opening the initial energizing circuit of the storage relays, at armature 545 completes the display circuit whereby the required number is displayed to the operator by the lighting of the appropriate call indicator lamps and at armature 546 connects a further earth to lead 553 to replace that which is removed by the de-

energization of relay 500 when its circuit is opened at armature 257. Since relay 539 energizes before relay 500 deenergizes this latter operation is effected without discontinuity and the storage relays remain operated. The deenergization of relay 500, however, removes earth from lead 526 whereby the operated set-up relays are deenergized and also the change over relays such as 517 and 531. The operation of relay 540 which takes place at this time opens another point in the connection to lead 552 and prepares a circuit for relay 541.

The condition of affairs so that only relays 217, 247 and 260 in the trunk relay group are energized and the marker and set-up control switch have been released as well as the de-coder proper. Only relays 539 and 540 remain energized and the storage relays which are effecting the display of the number to the operator. These conditions persist until the operator deals with the call.

Consider now therefore the state of affairs at the coder upon the completion of the sending of the code impulses. The code sending switch continues to operate in the manner described until it has made a complete revolution, i. e., until wiper 142 arrives once more on the contact connected to lead 139 which is not now earthed. When it reaches its twenty-third contact, however, wiper 142 finds earth through the low resistance relay 72 instead of direct and relay 72 is thereby energized. At its armature 73 it removes the locking earth from all the operated storage relays in the coder and also the change over relays 98, 117, 124, and 127 and these accordingly deenergize. Moreover at its armature 74 it completes the following circuit: from earth front contact and armature 74, lead 62, wiper 52, front contact and armature 42, front contact and armature 31, armature 6 and its front contact, armature 28 and its front contact, winding of relay 20 to battery. Relay 40 upon operating, at armatures 21 and 24 switches the speaking leads through at armature 22 opens the circuit of the busy relay 17 and at armature 23 completes a locking circuit for itself at the same time releasing the coder selector and the coder which then reverts to common use. The switching through of the speaking leads has no particular effect at the moment.

Returning now to the further progress of the call, the operator, upon noting the number displayed on the call indicator lamps, will take up a plug associated with a convenient idle cord circuit and will test the jack of the wanted subscriber by touching the tip of the plug against the ring of the jack. If the called line is busy a circuit will be completed as follows: battery through the winding of the sleeve relay such as 411 associated with another operator's cord, ring of jack, tip of plug, normally closed contacts controlled by

armature 412, lead 413, winding 414 of the induction coil to earth; this circuit will consequently induce a click in the operator's head set over the plug 415.

It will be assumed, however, in the present case that the wanted number is idle when called and consequently the operator will insert the plug fully into the subscriber's jack, whereupon a circuit is completed from battery, winding of relay 411, ring of plug, sleeve of jack, subscriber's cut-off relay to earth. The sleeve and cut-off relays operate in series and the latter clears the subscriber's line of its normal battery and earth connections in the usual manner. Relay 411 upon operating, at armature 412 disconnects the operator's head set and completes the upper speaking lead, at armature 418 lights the supervisory lamp 419 and at armature 417 completes a circuit for the rotary line switch associated with the cord as follows: earth, armature 417 and its front contact, normally closed springs controlled by armature 420, armature 421 and its back contact, winding of relay 404 to battery. Relay 404 thereupon energizes and starts the line switch hunting in the usual manner for the contact 274 associated with the trunk over which the call is to be completed from which earth was removed by the operation of relay 250. When the marked trunk is found, relay 405 is operated whereby the speaking leads from the calling subscriber are switched through, relay 404 is disconnected and earth is connected over wiper 403 to the test contact associated with the trunk line in use. A circuit is thereupon completed for relay 266 which operates and at armatures 223 and 228 cuts off the battery connections from the trunk line, at armature 267 places a further earth connection on release trunk 222 and at armature 269 completes a locking circuit for itself.

Furthermore at armature 269, relay 266 breaks the circuit of relays 260 and 539 so that both these relays deenergize, the former at armature 265 opening the circuit of relay 247 which also deenergizes. Upon the deenergization of relay 539 a circuit is completed for relay 541 which at its armature 548 opens the locking circuit of the storage relays so that they deenergized. Furthermore, at armature 545 the circuit for the lamps is broken so that the number displayed is extinguished. All the apparatus associated with the de-coder is thus released.

It may happen, however, if the operator is working at high speed that another call will have come to the decoder while she was completing the first. In this case all the appropriate set-up relays will have been operated and further operations will be awaiting the earthing of lead 552. This occurs when relay 540 deenergizes whereupon the storage relays are again operated in accordance with the new

number, a relay similar to 260 is energized and immediately afterwards relay 539 whereupon the new number is displayed. Thus after one number is dealt with and disappears the operator does not have to wait even the 5 short time required for the transmission of the code impulses, but the next number appears immediately.

To return now to the original connection. 10 When the speaking leads from the calling subscriber are switched through by the operation of relay 405, a circuit is completed over the loop from the repeater by way of normally closed springs controlled by armatures 422 and 423 for line relay 407. The current flow in this circuit is in such a direction that shunt field relay 15 is not operated. Relay 407, however, operates at armature 424 completes a circuit for relays 408 and 409 in parallel and removes one earth connection from 15 lead 472, at armature 425 extinguishes the supervisory lamp 419 and at armature 426 connects up the ringing generator RG to the called line by way of the lower winding of 20 ringing trip relay 410 and back contact and armature 427. Relay 408 operates when its circuit is completed, at armature 428 completes the ringing circuit, at armature 429 completes a locking circuit through its upper winding 25 to earth at armature 417 and at armature 428 alters the connection of the release trunk conductor 473 so that the earth thereon is no longer provided by armature 424 but by armature 417, so that the release of all the 30 operated apparatus with the exception of the cord circuit is under the control of the calling subscriber. Relay 409 also energizes and at armature 430 prepares a locking circuit for itself and at armature 431 prepares a new circuit 35 for the supervisory lamp 419.

Ringing will now take place in the usual manner until the called subscriber answers, whereupon ringing trip relay 410 will be energized through its lower winding by direct 40 current over the loop and will operate its armatures 427 and 432 to disconnect the ringing generator and at the former to complete the speaking leads and at the latter to complete a locking circuit for itself. As soon as armature 427 is operated, a circuit is completed 45 for the back bridge relay 406 which at its armatures 422 and 423 reverses the current back over the connection, at armature 433 completes the previously prepared locking circuit 50 for relay 409 and at armature 434 prepares a flashing recall circuit. In consequence of the reversal of current over the speaking leads, shunt field relay 15 in the repeater in the tandem exchange, Fig. 1, is now operated and at 55 its armature 16 completes a circuit for relay 44 which operates in turn and reverses the connections of the line relay 4 so that metering or like operations may be effected.

The connection has now been completely 60 established and the two subscribers may con-

verse. Speech current is supplied to the called party from the relay 406 in the cord circuit and to the calling party from the local trunk relay group and the speaking circuit is shown in thick lines.

70

At the end of the conversation when the calling subscriber hangs up, relay 4 is de-energized and opens the circuit of relay 7 which deenergizes also. The removal of earth from release trunk conductor 3 releases the 75 preceding switches and relays 15, 20, 25, 31 and 45 in the repeater are also released. Selector D therefore restores to normal and the consequent opening of the loop deenergizes line relay 407 which releases armature 80 424. The removal of earth from release trunk conductor 473 restores relays 202, 217, 266 and 403 so that the trunk line and the trunk relay set are again available for other calls. Relay 407 also completes a circuit at armature 85 425 for supervisory lamp 419 which again lights. When the called party hangs up, relay 406 is deenergized and opens the locking circuit of relay 409 which deenergizes also. Relay 408 however, is held up over its upper winding from earth at armature 417. Upon noting the lighted condition of the lamp 419, the operator will remove the plug from the jack, whereupon sleeve relay 411 deenergizes and opens the circuit of relay 408. The whole 90 of the apparatus involved is then restored to 95 normal.

100

Consider now the case when the called subscriber's line is busy when the operator tests his jack with the tip of her plug; in this case instead of inserting the plug the operator will press the busy key 411 of which only one is provided for each position. This operation results in the operation of the busy calls meter 450, the completion of a circuit for the 105 upper winding of relay 539 so as to prevent premature release of the storage relays and also the completion of a circuit which extends from earth at the busy key over its operated right hand spring, busy start common 110 lead 453, armature 248 and its front contact, front contact and armature 261, upper winding of busy relay 259 to battery. Relay 259 thereupon operates, at armature 271 connects busy flash battery and busy tone alternately 115 to the lower speaking leads, at armatures 225 and 228 connects both its windings across the trunk line in a locking circuit, at armature 270 opens the locking circuit of relay 260 which thereupon releases, and at armature 275 connects earth to release trunk conductor 120 222 so as to maintain the secondary line switch operated. The calling subscriber thereupon hears the busy tone and realizes that he cannot obtain his connection and accordingly hangs up. When he does so the busy relay 259 deenergizes and the whole connection is released in the previously described manner.

125

It should be noted that though the lead 130 453 from the busy key is common to all the

trunks in the position there is no possibility of a busy signal being sent out on the wrong trunk line since only that line over which the number which is being displayed was transmitted will have both the relays similar to 247 and 260 operated and without the operation of both these relays no circuit can be completed for busy relay 259. Clearly also it is only necessary for the operator to press the key 441 momentarily.

The operation will now be considered of dealing with special calls which are extended over a limited number of special service trunks to a special service operator's position. The operation as far as the call indicator operator is concerned is very similar to that which takes place when a called line is found busy. In this case, however, the operator presses the special service key 444, which at the right hand contacts closes a circuit for the special service calls meter 449 so that the number of special service calls is recorded and at its left hand contacts completes a circuit from earth over the special service start common lead 454 to the relay 350 of the special service trunk distributor and also over wiper 352 and contact 353 with which it is in engagement, lead 455, winding of relay 456 to battery. Relay 350 energizes in this circuit and at armature 358 opens the circuit of the rotary magnet 354 of the special service trunk distributor. Relay 456 also operates and at its armature 457 locks itself up to earth at armature 460 so that the special service key 444 need only be pressed momentarily and at armatures 458 and 459 completes circuits for initiating the hunting movement of the switch in well known manner.

The special service position trunk finder thereupon rotates its wipers in search of the trunk associated with the displayed number in the same manner as was done by the rotary line switch associated with the cord circuit in the connection previously described. When the switch finds the trunk line from the test contact of which earth has been removed at armature 264, relay 465 is no longer short circuited and energizes, at its armature 460 opens the circuit of relay 456 and at the front contact of this armature completes a circuit over lead 471 for the rotary magnet of the special service trunk distributor, at armature 461 prepares a locking circuit for itself and at armature 462 connects earth to test contact 274 thereby operating relay 266 with the previously described results. Relay 465 also at its armatures 463 and 464 bridges relay 466 across the trunk line and it thereupon operates and at armature 467 completes a locking circuit for relay 465 and at armature 468 feeds earth forward to the special service trunk finder. When armature 467 leaves its back contact, one earth connection is removed from common lead 492; clearly therefore when all the special service trunks are in use, no earth

will be connected to lead 492. Under these circumstances, relay 355 is no longer short circuited and energizes, at armature 357 opens the circuit of the rotary magnet 354 of the special service trunk distributor and at armature 356 lights the all special service trunks 70 busy lamp 445.

When earth is connected over lead 476 to the special service trunk finder, a circuit is completed for line relay 479, which operates 75 and initiates the trunk hunting movement of the switch in the usual manner. When an idle special service trunk is found, relay 480 is no longer short circuited and operates, thereupon at its armatures 483 and 484 connecting the earth on lead 476 over test wiper 494 to relay 485 at the special service trunk operator's position and at armatures 481 and 482 completes the speaking circuit over leads 477 and 478. Relay 485 thereupon energizes, at armature 486 lights the lamp 488 and at armature 487 connects the retardation coil 489 across the jack springs so as to prepare the talking circuit for the operator. When the operator plugs in, sleeve relay 490 is operated 80 and at its armature 491 opens the circuit of the lamp 488. The special service operator can then deal with the matter in question and the connection will be released in the usual manner when the calling subscriber hangs up. 85

It will be noticed that in addition to the meters previously referred to for counting the number of special service calls and also the number of busy calls, a meter is provided for counting the total number of calls dealt 90 with at a position, this being operated on the energization of relay 452 which is connected in series with the call indicator lamps and is accordingly operated whenever a fresh 95 number is displayed.

The flashing busy recall feature also should be briefly described. Suppose that both subscribers have hung up but that the operator does not immediately take down the connection and that in the meantime the called subscriber again removes his receiver in order to initiate a call himself. Prior to this operation all the relays in the cord circuit will be de-energized with the exception of the sleeve relay 411. When the receiver is removed at 100 the called substation, relay 406 will be energized and the following circuit will thereupon be completed: battery, supervisory lamp 419, armature 418 and its front contact, back contact and armature 425, armature 434 and its 105 front contact, armature 431 and its back contact, lead 473, winding 438 of the induction coil, winding of relay 436 to earth over an interrupter. In consequence of the completion of this circuit, lamp 419 will flash intermittently and the operator will receive an audible signal in her receiver owing to the intermittent current through winding 438. The resistance provided shunting the lamp 419 ensures that in case the lamp should be burnt 110 115 120 125 130

out, under which circumstances the operator would get no clearing supervision, she may still get an audible signal and the called subscriber will not be tied up. The intermittent 5 operation of relay 436 however can be arranged at its armature 437 to operate the recall buzzer 439 if the key 440 has been pressed.

The arrangements for preventing the accumulation of more than a certain number, 10 say five uncompleted calls at an operator's position will now be considered. It will be seen that in case there is an earth connection on lead 246, relay 239 in the position load distributing switch will be energized over 15 wiper 243, when this wiper arrives at the contact 245 associated with the position in spite of the fact that relay 233 has not been operated: hence the load distributing switch will step on and no call will be allotted to this 20 position. The connection of earth to lead 246 may be effected for any one of three reasons, firstly because the operator has left the position, secondly because all the cords at the 25 position are in use and thirdly because five calls are awaiting attention. The two first cases are taken care of by relay 442. This it will be seen is normally energized in the circuit: battery, winding of relay 442, outer contacts in the plug 415, common lead 274 30 to earth at the back contacts of armature similar to 424. Consequently this relay will be maintained energized unless the plug 415 has been removed owing to the operator leaving her position or in case all the cords are in 35 use, in which event all the armatures similar to 424 will be operated and there will be no earth on common lead 474. Under these circumstances, relay 442 de-energizes and at armature 443 places earth on lead 246. In 40 case five calls are awaiting attention each of the five markers will be in use and in each one the armature, such as 306 will have left its back contact. In consequence earth is removed from lead 337, relay 321 is no longer 45 short circuited and on energizing at its armature 322 connects earth to lead 246 with the previously described results. At the back contact of this armature earth is removed from one contact in the bank of wiper 319 of 50 the marker distributor so that this shall not continue rotating when there are no more idle markers to be allotted. Relay 321 also at its armature 323 completes a circuit over lead 492 for the position over load lamp 447 and 55 mon relay 448. Lamp 447 is therefore lighted to indicate to the supervisor which position is overloaded and by the operation of relay 448 an alarm buzzer 447 is sounded to attract the supervisor's attention.

60 It has been pointed out in connection with the repeater, Fig. 1 that since the coder selecting switch has the duration of a whole train of impulses as well as two pauses in which to complete its hunting operation, there 65 is no danger that it will not have time to test

all the coders provided. There still remains, however, the possibility that all the coders may be in use and to deal with these circumstances, relay 17 is provided.

Suppose that all the coders are in use and hence that when the subscriber dials the first digit which should go to the coder, the coder selector is still hunting, consequently relay 38 is not operated. Upon the first deenergization of relay 4, a circuit is completed as follows: earth, armature 10 and its front contact, front contact and armature 29, back contact and armature 6, armature 30 and its front contact, armature 42 and its back contact, back contact and armature 22 lower winding of relay 17 to battery. Relay 17 thereupon operates, at armature 19 connects busy tone to the lower trunk conductor and at armature 18 opens the circuits of relays 25, 31 and 38 and completes a locking circuit 85 for itself over its upper winding. The calling subscriber therefore hears the busy tone and hangs up, whereupon the partially established connection is released in the usual manner.

90 A special feature will now be described whereby in case the calling subscriber hangs up after the transmission of the code impulses has commenced but before the number has been displayed to the operator, the connection is released and the number is not displayed. Previously the sequence of operations was that the operator plugged into the jack of the called subscriber but no ringing took place and she immediately received the disconnect 95 signal and took the connection down. It should be pointed out that once the coder has started sending, it is necessary for it to complete its rotation and send the complete code train in order that all the operated apparatus 100 may be restored to its normal position; consequently while this operation is taking place control of the release of the connection is temporarily removed from the calling subscriber. When the sending of all the four 105 digits has been completed and the relay 531 operates, relay 543 is connected to the lower speaking lead in the following circuit: battery, winding of relay 543, armature 550 and its front contact, armature 528 and its front contact, lead 277, front contact and armature 227, back contact and armature 226, lead 221. If the calling subscriber has hung up at this 110 time, a circuit may now be traced from conductor 48, armature 24 and its back contact, armature 43 and its back contact, lower winding of relay 31 to earth. Both relays 543 and 31 energize in this circuit and the latter by maintaining armature 32 operated keeps 115 earth on the release trunk conductor 49 and prevents the repeater and trunk line being seized before all the apparatus has been released. Relay 543, by operating its armature 551, connects battery over lead 279 to the junction point of relays 212 and 254 whereupon 120 125 130

relay 212 is shorted out and deenergizes thereby at armature 214 opening the circuit of relay 254 which deenergizes also. The decoder is then released and the number which has been stored on the set up relays is not displayed: thus the operator does not have to do unnecessary work by setting up and taking down an unwanted connection.

It will be noticed that since the circuit of relay 542 is opened at armature 536 at the same time as relay 543 is connected up at armature 528, this connection of battery to the lower trunk conductor is only momentary and if the calling subscriber is still on the line it will be without function.

A further case must also be considered, namely that in which the operator for some reason or other delays to set up the number which has been displayed. At this stage, it will be remembered, relays 217, 247 and 260 in the trunk relay set have been operated. Relay 260, however, at its armature 229 connects battery to trunk lead 221 in place of the normal earth connection, so that the circuit for relay 31 previously described is completed and under these circumstances this circuit is maintained until the operator plugs in or presses the busy or special service key. In case therefore the calling subscriber should have hung up, the trunk line is guarded against seizure by any other switch such as selector D until all the apparatus which has been operated has been released.

The decoder release key 435 is provided for releasing the decoder in case the code sending switch should be held up for any reason during the sending of a code train. The effect of the operation of the key 435 is to connect earth to lead 552 so that relay 260 is energized and to complete the circuit of the busy relay 259. The decoder is thus released and may be used for setting up other calls, while the subscriber receives the busy signal and hangs up. Thereupon the trunk line is released and the repeater is no longer associated with the coder to the condition of which the attention of an attendant is then called by means of a suitable alarm system.

Having now particularly described and ascertained the nature of my said invention and in what manner the same is to be performed, I declare that what I claim is:

1. In a telephone system, a calling line, automatic switching mechanism controlled over said line in accordance with a portion of a desired number to extend a connection toward a called line, and a register sender controllable over said calling line over a circuit path independent of the operated switching mechanism to register a further portion of the desired number and to transmit impulses representing such portion over a circuit path including the operated switching mechanism.

2. In a telephone system, a trunk line, a

hunting switch, an impulse responding device, means responsive to the extension of a connection to said trunk line for starting said hunting switch to effect a connection between the trunk line and said impulse responding device, an automatic switch controlled over said trunk line responsive to the first series of impulses received thereover to extend a connection toward a desired line, and means also responsive to the first series of impulses for routing the remaining series of impulses away from said automatic switch to said impulse responding device through said trunk-hunting switch.

3. In a telephone system, a trunk line, a registering device, means for transmitting a plurality of series of impulses over said trunk line, an automatic switch responsive to the first series of impulses coincidentally with the transmission thereof to extend the connection toward the desired line, and means responsive to such series for rendering said registering device responsive to the remaining series of impulses.

4. In a telephone system, a trunk line, a registering device including a plurality of digit registers and a digit-steering device, means responsive to the seizure of said trunk line for connecting said registering device therewith, means for transmitting two series of impulses over said trunk line, and means responsive to the first series of impulses for rendering said registering device initially responsive to the second series of impulses.

5. In a telephone system, a trunk line, means for transmitting a series of impulses over said trunk line, an automatic switch directly responsive to said impulse series, a second impulse transmitting means, and means for delivering the impulses generated by the second impulse transmitting means through the connection set up by said automatic switch over a circuit path excluding said trunk line.

6. In a telephone system, a trunk line extending to an automatic switch, means for transmitting a plurality of series of impulses over said trunk line and for delivering the first series of impulses to said automatic switch, a register sender, means responsive to the first series of impulses for diverting the remaining series away from said automatic switch to set the registering portion of said register sender, and means in said register sender for transmitting a plurality of series of impulses through the connection set up by said automatic switch over a circuit path excluding said trunk line.

7. In a telephone system, an automatic office and a plurality of manual offices, a trunk line in said automatic office extending to a manual office selector, a register sender in said automatic office, means for extending a connection to said trunk line and for sending a plurality of series of impulses thereover,

- means for directing the first series of impulses to said automatic switch to operate the same to extend a connection to the desired manual office, means for diverting the remaining series of impulses away from said automatic switch to said register sender to set the registering portion thereof, indicating apparatus in said manual offices, and means in said register sender for transmitting series of impulses through said automatic switch over a circuit path independent of said trunk line to operate the indicating apparatus in the selected manual office to indicate the number of the desired subscriber.
8. In combination, a step-by-step switch having three wipers, a plurality of groups of storage relays, means for operating said switch in response to each of a plurality of digits, and means controlled over the three wipers of the switch for recording each digit in the corresponding storage relay group by operating the relays in the combination corresponding to the instant registered digit.
9. In a telephone system, a plurality of lines differing in resistance, an impulse sender for transmitting impulses differing only in strength, means for connecting said impulse sender with any one of said lines, and means for regulating the resistance of the impulse circuit in said sender so that the over all resistance of the impulse circuit and the line circuit is substantially the same regardless of the line to which the sender is connected.
10. In a telephone system as claimed in claim 9, a registering device in said sender for registering a digit not forming part of the desired telephone number and for controlling said regulating means in accordance with the digit registered.
11. In a telephone system as claimed in claim 9, a registering device in said sender for registering a digit not forming part of the desired telephone number and for controlling said regulating means in accordance with the digit registered, a plurality of other registers for controlling said sender, means for operating said registers in accordance with a plurality of digits in the desired telephone number, and means for operating said regulating register prior to the operation of the last named register.
12. In a telephone system, trunk lines differing in electrical characteristics, a register sender for registering and retransmitting telephone numbers over any one of said trunk lines, further means in said register sender for registering a digit not forming part of a telephone number, and means controlled by said further means for varying the electrical characteristics of the impulse transmitting circuit in accordance with the length of the instant trunk involved in the connection.
13. In a telephone system, an automatic office and a manual office, registering and display apparatus in said manual office, a regis-
- ter sender in said automatic office, means for extending a connection from a calling line in said automatic office by way of an inter-office trunk line to said manual office, means for associating said register sender with said connection, means included in said register sender for transmitting the desired number over the engaged inter-office trunk line to set the registering apparatus in the manual office, means for operating said display means at the end of the registration of said number, and means for momentarily preventing the operation of said display means and for testing the connection to determine whether or not the calling subscriber has abandoned the connection.
14. In a telephone system, an automatic office and a manual office, registering and display apparatus in said manual office, a register sender in said automatic office, means for extending a connection from a calling line in said automatic office by way of an inter-office trunk line to said manual office, means for associating said register sender with said connection, means included in said register sender for transmitting the desired number over the engaged inter-office trunk line to set the registering apparatus in the manual office, means for operating said display means at the end of the registration of said number, means for momentarily preventing the operation of said display means and for testing the connection to determine whether or not the calling subscriber has abandoned the connection, and means for wiping out the registration without effecting a display in case the calling subscriber has abandoned the connection.
15. In a telephone system including automatic offices and manual offices and in which registering and display apparatus is located in the manual office to register and display manual numbers called by the automatic subscribers, testing means effective subsequent to the registration of a number and prior to its display for momentarily halting the display and for wiping out the registration and preventing the display in case the calling automatic subscriber has abandoned the connection.
16. In a telephone system, an operator's switchboard, trunk lines incoming to said switchboard over which regular connections and special connections may be completed, operator controlled means at said switchboard for completing all said regular connections, and switching means under the control of the operator and independent of the regular switching equipment for trunking all special connections to a second operator's switchboard.
17. In a telephone system, an operator's switchboard, trunk lines incoming thereto, means for extending partially completed regular connections and partially completed

- special connections to said switchboard over said incoming trunk lines, manual connecting means at said switchboard for completing the regular connections, and operator-controlled automatic means at said switchboard 5 operated independent of said manual connecting means for completing the special connections.
18. In a telephone system, an operator's switchboard, trunk lines incoming to said switchboard, means for bringing in calls on said trunk lines one at a time, means at said switchboard for completing regular connections coming in over said trunk lines, a second 10 switchboard for completing special connections, non-numerical automatic switching means, and means controlled by the operator when a special connection comes in over a given trunk line for operating said non-numerical automatic switching means to connect said given trunk line to said second 15 switchboard.
19. In a telephone system, an automatic office and a manual office, trunk lines extending 20 from said automatic office to said manual office, call storing means in the manual office associated with said trunk line, means for transmitting a number over a trunk line and for storing it in said manual office until the 25 operator has completed the connection, and means controlled from said manual office responsive to the storing of a number indicating a non-completed connection for maintaining the interoffice trunk line guarded in 30 the automatic office independent of the calling 35 automatic subscriber.
20. In a telephone system, a plurality of switchboards, separate groups of trunk lines leading to said switchboards, respectively, a group of lines common to all said switchboards, automatic switching mechanisms responsive to calls over said common group for effecting a connection between any one of said common lines and trunk lines leading 40 to any one of said switchboards, and a distributing device operative in successive stages for causing the said mechanism to direct the calls successively to said switchboards.
21. In a telephone system, a plurality of 45 switchboards, a separate group of trunk lines extending to each switchboard, a group of trunk lines common to all said switchboards, means normally effective for rendering all the idle trunks at each switchboard artificially busy, and means for removing the artificial busy condition from the separate trunk line groups successively.
22. In a telephone system, a plurality of 50 groups of trunk lines, a group of trunk lines common to the plurality, means for making all the idle trunk lines in each of the first named groups artificially busy, distributing means effective to remove the artificial busy 55 condition at any one group of trunk lines,
- and means controlled by the establishment of a connection between a trunk line in the common group and one of the idle trunk lines for advancing said distributing means to replace the artificial busy condition and to remove it from the succeeding group. 70
23. In a telephone system, a manual switchboard, trunk lines incoming thereto, automatic switches having access to said trunk lines and others, means for placing an artificial busy condition on all the idle trunk lines incoming to said switchboard, means for removing said artificial busy condition at intervals, a plurality of cord circuits at said switchboard for completing connections incoming over said trunk lines, and means controlled by the busy condition of all said cord circuits for preventing the removal of the artificial busy condition. 75 80
24. In a telephone system, a manual switchboard, trunk lines incoming thereto, automatic switches having access to said trunk lines and others, means for placing an artificial busy condition on all the idle trunk lines incoming to said position, means for removing said artificial busy condition at intervals, and means controlled at the will of the operator at said switchboard for preventing the removal of the artificial busy condition. 85 90
25. In a telephone system, a manual switchboard, trunk lines incoming to said switchboard, means for seizing any one of said trunk lines and for making it busy while it is seized, means for making all the idle incoming trunk lines artificially busy, and means for removing the artificial busy condition at intervals. 100
26. In a telephone system, a plurality of manual switchboards, a separate group of trunk lines incoming to each switchboard, means common to all said trunk lines for extending a connection to any one of them, means at each switchboard whereby the operator can complete the connection extended to any trunk line at her switchboard, means for rendering all the idle trunk lines at all switchboards artificially busy and for removing the artificial busy condition at the several switchboards, successively, and means for preventing the removal of the artificial busy condition from the idle trunk lines at any given switchboard in case there exists more than a predetermined number of completed 105 110 connections. 115
27. In a telephone system, a plurality of operator's switchboards, a separate group of trunk lines incoming to each switchboard, call markers at each switchboard less in number than the number of the trunk lines incoming to said switchboard, means responsive to a call over any trunk line for connecting an idle marker thereto, means responsive to the handling of the connection by the op- 120 125 130

erator for disassociating the marker from the trunk line, means for making all the idle trunk lines at each position busy artificially and for removing the artificial busy condition at the various switchboards successively, and means for preventing the removal of the artificial busy condition at any switchboard when all the markers thereat are in use.

28. In a telephone system, a plurality of exchanges located varying distances from each other, means including trunk lines connecting one of said exchanges with any of the others, sending equipment at said one exchange for operating equipment in the exchange connected with comprising means for transmitting impulses varying in strength to variably operate the equipment at that exchange, and means for automatically compensating for any variation between the resistances of the various trunks due to their variation in length.

29. In a telephone system, a trunk line terminating in an automatic switch, a preceding switch having access to said trunk line, a register, switching mechanism operative after the seizure of said trunk line by said preceding switch for associating said register with said trunk line, means for sending impulses over said trunk line, a second trunk line, means responsive to one series of impulses sent over said trunk line for operating said automatic switch to connect with said second trunk line, and means for then registering other series of impulses sent over said trunk line on said register.

30. In a telephone system, a trunk line, an automatic switch having a directive movement and a hunting movement terminating said trunk line, means for sending series of impulses over said trunk line, means responsive to one series of impulses for controlling the directive movement of said switch, registers, switching mechanism operable during the sending of said one series of impulses for associating an idle register with said trunk line, means in said switch for starting its hunting movement upon the completion of its directive movement, and means for rendering the associated register effective to register the next series of impulses when sent before the completion of the hunting movement of said automatic switch.

31. In a telephone system, a trunk line extending to an automatic switch, means for operating said switch responsive to a series of directive impulses transmitted over said trunk line to extend a connection towards a called line, a group of registers, and means operated during the movement of said switch for selecting an idle register and connecting it to said trunk line.

32. In a telephone system, a trunk line extending to an automatic switch, means for sending series of impulses over said trunk line

to said switch, a group of registers, and means operative while one series of impulses is being sent for associating an idle register with said trunk line.

Signed by me at Liverpool, England, this 26th day of September, 1924.

JOHN E. OSTLINE.
